(57) **CLAIM**

The ornamental design for a limited flow beverage container, as shown and described.

DESCRIPTION

FIG. 1 is a perspective view of a limited flow beverage container showing our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The greyscale shading shown in FIGS. 1-7 is provided solely for the purpose of showing surface contours and forms no part of the claimed design. The dash-dot lines in FIGS. 1-7 and the areas within the dash-dot lines shown in phantom show portions of the limited flow beverage container that form no part of the claimed design.
